UNITED STATES PATENT OFFICE

2,533,434

HAIR CURLER

Richard T. Clifton, Detroit, Mich.

Application April 14, 1947, Serial No. 741,349

1 Claim. (Cl. 132—43)

1

My invention relates to a new and useful improvement in a hair curler embodying parts about which a strand of hair is wound for curling the same.

It is an object of the present invention to provide a hair curler of this class which will be simple in structure, economical of manufacture, durable, compact, light, and highly efficient in use.

Another object of the invention is the provision of a hair curler of the class described so constructed and arranged that a strand of hair wound thereon and retained thereon a sufficient length of time will be provided with a curl having a spiral formation.

Another object of the invention is the provision of a hair curler of this class having a base and a pair of bendable members projecting upwardly therefrom and inclining and converting relation to the base to provide a cone-like structure about which the strand of hair will be retained by the retaining arms or bendable portions.

Other objects will appear hereinafter.

It is recognized that various modifications and changes may be made in the detail of structure illustrated without departing from the invention itself and it is intended that such shall be embraced within the scope of the claims which form a part hereof.

Forming a part of this specification are drawings in which,

Fig. 1, is a perspective view of the invention,

Fig. 2, is an enlarged sectional view taken on line 2—2 of Fig. 1 with parts broken away,

Fig. 3, is a sectional view taken on line 3—3 of Fig. 2,

Fig. 4, is a perspective view of the invention showing it in use.

As shown in the drawings, the curler comprises a member preferably formed from a single piece of easily bendable metal and embodies a base 8 having the doubled-over portions 9 and 10 which connect by the inclined portions 11 and 12 with the bendable arms 13 and 14, the arm 13 being longer than the arm 14. These arms 13 and 14 may be termed retaining arms as their function is to retain the strand 18 of hair in position when it is wound for the purposes of curling. As shown clearly in the drawing, the upper face of the central portion of the base 8 is concave to provide the curved rib 19 extending below. Each of the inwardly turned portions 9 and 10 is provided with an outwardly projecting curved rib 20 and the members 11 and 12 are also provided with

2

this outwardly curved rib 15. In use, the strand of hair 18 is separated from the rest of the hair and the curler is then placed with the base resting upon the scalp. This strand is then wound manually around the retaining arms 13 and 14 at the base thereof so that the center of the curl is centered on the inclined or conical forming portions 11 and 12. The retaining arms 13 and 14 are then bent downwardly into the dotted line position shown in Fig. 3 to securely hold this strand of hair in wound position. When left in this position a sufficient length of time, the hair will retain its curl.

By forming the ribs 15 and 20, the strand of hair wound upon the portions 11 and 12 and the retaining arms 13 and 14 is prevented from coming into contact with the sharp edges. Likewise, the rib 20 prevents the strand of hair from being pressed against the sharp edges of the doubled-over portions 9 and 10 when the retaining arms 13 and 14 are bent downwardly into clamping position. By forming the rib 19 on the under surface of the base 8, the engagement of the sharp edges of the base with the scalp is avoided and thus a more comfortable device is provided.

By having the portions 11 and 12 inclined as indicated, a conical formation is thus effected about which the strand of hair is wound so that the curl centers around this conical formation. The result is that the curl assumes a more natural, spiral-like formation when the curler is released from the strand.

Experience has shown that the curler constructed in this manner is one which is most efficient in use and provides a curl of very attractive appearance, while at the same time, the device is economically manufactured and, because of its construction and lightness, easily worn without discomfort to the user.

40 What I claim as new is:

A curler of the class described, comprising: a base; a pair of arms carried by said base projecting upwardly therefrom on opposite sides thereof, each of said arms being bent inwardly to overlie, 45 in parallel relation, a portion of said base and each of said arms being bent outwardly from said base, outwardly from the center thereof and angularly to said base, said arms converging to meet at a point centrally of said base, and each of said 50 arms being extended outwardly from the point of converging, the angularly turned portion of said arms providing a core for a lock of hair wound thereon to provide a curl, and the outwardly projecting ends of said arms being bendable outwardly from each other and downwardly toward said

base for clamping the curl on said core and said base, the faces of said arms being engaged by the hair being curved in cross-sections at the central portion thereof with the convex side thereof engaging the hair.

RICHARD T. CLIFTON.
